UNITED STATES PATENT OFFICE.

ROBERT V. CRADDOCK, OF CAMBRIDGE, IDAHO.

TERMINAL PULLER.

Application filed February 25, 1928. Serial No. 257,017.

This invention relates to terminal pullers for removing the terminals of storage batteries.

An important object of the invention is to provide a unitary tool embodying plier-connected jaw implements, which may be used to withdraw a terminal where the same is badly corroded or too firmly engaged with the terminal post and a pressure bar to be employed with the jaw implement in event it is found that an ordinary pull will not remove the terminal.

A further object of the invention is the provision of a structure such that these elements may be readily and conveniently combined.

These and other objects I attain by the construction shown in the accompanying drawings, wherein for the purpose of illustration is shown a preferred embodiment of my invention and wherein:—

Figure 1 is a side elevation of a terminal puller constructed in accordance with my invention;

Figure 2 is an edge elevation thereof. —

Referring now more particularly to the drawings, the numerals 10 and 11 indicate plier-connected members, each having one end in the form of a jaw 12 and the other end in the form of a handle 13. Said elements at the decussation thereof are widened and furcated, one of the elements being directed through the furcation 14 of the other. A pivot 15 is passed through this decussation and will, of course, be exposed at the furcation 16 of the first named element. The exposed portion of the pivot has formed therethrough a vertical bore 17 through which is directed a plunger 18 having at its upper end and between the handle sections 13 a head 19. Pivoted to one of the handle sections is a bell crank lever having a short arm 20 and a long arm 21. The short arm 20 has an angular portion provided with a cam face 22 overlying the head 19, while the upper end of the long arm is formed as a handle 23. The jaws 12 are provided with opposed engaging flanges 24, the extremities of which are sharpened and the upper faces of which are preferably straight and perpendicular to the jaws, as indicated at 25.

In the use of the tool, the handles 13 are grasped to force the engaging flanges 24 into the terminal. Under most circumstances, a pull upon these handles, after the flanges are properly engaged in the terminal,

will suffice to remove the terminal. When the terminal is stubborn, after the flanges have been engaged therein, the handle 23 and the handle 13 of the plier member 10 are engaged with the hands. This operation tends to force the plunger 18 downwardly and at the same time to force the jaws 12 toward one another, with the result that the grip upon the terminal is maintained and a considerable pressure exercised against the post to force the terminal therefrom.

It will be obvious that such a structure may be very conveniently manipulated and may be relatively cheaply produced. Since the construction hereinbefore set forth is capable of a certain range of change and modification without materially departing from the spirit of the invention, I do not limit myself to such specific structure except as hereinafter claimed.

I claim:—

1. In a battery terminal puller, a pair of plier-connected elements including jaws for engagement with the terminal and a plunger for simultaneously engaging a post upon which the terminal is mounted, and means engageable simultaneously with the handle of one of the plier-connected elements for forcing the handle of the other of the plier-connected elements toward the first named handle and for shifting said plunger longitudinally to exert pressure upon the terminal.

2. In a battery terminal puller, decussate elements pivoted at the decussation and each formed at one end with a jaw and at its opposite end with a handle, a plunger slidably directed through the pivot to move in the general direction of the axis of an element disposed between and engaged by said jaws, and means engageable simultaneously with the handle of one of said elements for forcing the handle of the other of the elements toward the first named handle and for shifting said plunger longitudinally.

3. In a battery terminal puller, decussate elements pivoted at the decussation and each formed at one end with a jaw and at its opposite end with a handle, a plunger slidably directed through the pivot to move in the general direction of the axis of an element disposed between and engaged by said jaws, and a lever pivoted to the handle of one of said elements and having at one end a handle extending upwardly between the handles of

the elements, the opposite end of the lever means for simultaneously shifting said jaws being in the form of a cam engaging said toward one another and shifting said plunger longitudinally.

10

4. In a battery terminal puller, a pair of jaws for engagement with a terminal and a plunger for simultaneously engaging a post upon which the terminal is mounted, and

In testimony whereof I hereunto affix my signature.

ROBERT V. CRADDOCK.
